SOFA BED

Philip Cutler, New York, N. Y.

Application January 8, 1941, Serial No. 373,632

7 Claims. (Cl. 5—38)

This invention relates generally to a sofa bed having end members and an inclined back member, and has as a main object means for converting the same into a double bed by releasing the back member and allowing the same to pivot outwardly and downwardly about the end members whereby the back member forms an adjacent bed.

A further object of the invention resides in the provision of a sofa bed wherein the back member is completely separable from the horizontal portion to form a companion or twin bed therewith.

A further object of the invention resides in the provision of a convertible sofa bed which is economical to manufacture, easy to operate, composed of a minimum number of parts and which is adapted to furnish an article of furniture of aesthetic appearance.

These objects and other incidental ends and advantages of the invention will hereinafter appear in the progress of the disclosure and as pointed out in the appended claims.

Accompanying this specification are drawings showing a preferred embodiment of the invention wherein corresponding reference characters designate corresponding parts throughout the several views and wherein:

Figure 1 is a view in perspective showing my construction assembled in the form of a sofa bed.

Figure 2 is a sectional view of Figure 1 along the plane 2—2 thereof.

Figure 3 is an end view of the sofa bed partly in section showing progressive positions of the back member of the sofa bed toward attainment of a horizontal position.

Figure 4 is a plan view of the sofa bed with the back member in extended and horizontal position.

Figure 5 is a rear view of the sofa bed with the back member in extended and horizontal position.

Fig. 6 is a partial plan view of one end of the back member frame.

Figure 7 is a partial view in perspective of one of the guide ways for the back member secured to an end member of the sofa bed.

Figure 8 is a fragmentary transverse sectional view showing the connection between the end members of the sofa bed and the main frame.

In accordance with the invention and in accordance with the preferred form shown in the drawings, the sofa bed generally indicated by numeral 10 consists of end members 11 and 12; a main stationary frame 13; a back frame 14; forward and rear ornamental members 15, 16 and 15a, 16a respectively depending from the end members 11 and 12; seat or main frame cushions 17; back frame cushions 18; and front and rear castors 19, 19 and 20, 20 depending from the bottom transverse angles 30, 30 of the main frame which latter is now to be described.

The main frame 13 is comprised of a top front horizontal angle and a rear top horizontal angle 25, 25 while numeral 26 represents a bottom front horizontal angle and 27 represents a bottom rear horizontal angle. A front stiffening upright 28 is disposed between the front top and bottom horizontal flanges 25 and 26. Joining the ends of the top horizontal angles are transverse angles 29, 29 and joining the ends of the bottom horizontal angles are transverse angles 30, 30, the latter being extended rearwardly beyond horizontal angle 29 to accommodate castors 20, 20 as best shown in Figure 2. There are four vertical angles each represented by numeral 31 disposed between the top and bottom transverse angles 29 and 30.

A front wall or panel 34 is applied to the main frame and is hinged thereto whereby an entrance may be made into the interior of the frame for storage purposes. Thus, a latch 32 is secured to the top front horizontal angle 25 and is adapted to be in detachable engagement with a hasp 33 secured to the inner surface of the front wall of panel 34, the latter being hinged secured near the lower edge by hinges 35 to the bottom front horizontal angle 26. By raising latch handle 37 projecting above the upper wall of angle 25, the latch finger becomes free of the hasp 33 thereby permitting the panel 34 to fall outwardly about hinges 35. The panel is provided with conventional supporting chains 35a at each end, said chains being preferably attached to the front uprights 31. To close panel 34, it is merely necessary to swing the same into vertical position 35 for automatic latching.

Conventional bedding springs are drawn across the top of the main frame such as springs 39 drawn between the top transverse angles 29, 29 while the bottom of the main frame is formed by the use of three transverse strips 40 spaced apart and extending from the bottom front horizontal angle 26 to beyond the rear horizontal angle 21, the said strips penetrating the angle 27 at the vertical wall thereof at openings 43. The strips 40 terminate rearwardly in brackets 41 to support a shelf 42 for the back cushions 18 when the sofa bed is used as a sofa. Across the transverse strips 40 are elongated boards 44 forming the flooring of the storage compartment. The end walls of the compartment are formed by the end members 11 and 12 of the studio bed and are secured to the main frame by means of conventional bolts or studs 45 proceeding from the end members 11 and 12 and penetrating the corner vertical angles 31, the ends of the said studs 45 being held to the angles 31 by nuts 46 as shown in Figure 8.

Back frame 14 is comprised of upper longitudinal angles 61, 61; end transverse short angles 62, 62; a brace 63 between angles 62, 62 and con-

ventional bedding springs 64 drawn between the transverse angles 62, 62. Near each of the ends of horizontal angles 61, 61 is a leg angle 65 secured thereto by means of a pivot 72, the transversely opposite leg angles being joined by base angles 66 to which castors 67 are mounted. A U-shaped operating bar 69 is secured to the upper horizontal angles 61, 61 at the leg portions by pivots 70, 70, the said operating bar being connected to the frame legs 65, 65 by means of operating rods 71, 71 whereby the legs 65 are forced to collapse and to be vertically extended by movement of the base portion of operating bar 69. Links 73, 73 are secured to the legs 65, 65 to which operating rods 71, 71 are secured, the said links 73, 73 at the opposite ends being secured to locking bars 74, 74. Locking bars 74, 74 intermediate the ends thereof are pivotally secured to the transverse angles 62, 62 at pivots 75, 75, the opposite ends of the said bars 74 having locking projections 76, 76 which penetrate holes 77, 77 in the transverse angles 62, 62 as best shown in Figure 6 of the drawings. The legs 65 at the upper ends thereof adjacent the pivots 72 are provided with inclined clearance cuts 78 so that when the legs 65 are in collapsed position, they are permitted to be nested under the horizontal angles 61, 61. Furthermore, when the legs 65 are in vertical or outwardly inclined and maximum outstretched position as a result of the movement of operating bar 69 shown in Figure 5, locking projections 76, 76 are disengaged from holes 77, 77.

The back or movable frame 14 is adapted to slidably engage the end members 11 and 12 by means of a pair of aligned trunnions 68, 68 extending at the ends of the lower horizontal angle 61, the said trunnions slidably engaging a pair of opposing guide members 50 secured to the inner walls of the end members adjacent the rear ends. Each of the guide members consists of an elongated and rearwardly inclined track portion 57, the inner wall 51 of which is curved forwardly at the upper end as at 52 and continued to form a horizontal supporting track portion 53. The outer wall 55 of track 57 is spaced from and parallel with inner wall 51, the outer wall 55 having an overhanging top strip 54, whereby each trunnion 68 is maintained in the track, while 58 is a guard member for the tracks on the inner walls of members 11 and 12 all as shown in Figure 7. An end stop 56 for trunnions 68, 68 is preferably provided at the bottom of each track 57 so that frame 14 may be supported in inclined upright position, while end stop 56' at the end of the horizontal track portion 53 prevents trunnion 68 from further movement. It is unnecessary to utilize end stop 56' because the rear horizontal angle 25 of frame 13 would abut the lower or forward horizontal angle 61 of the rear frame 14. Trunnions 68, 68 are rotatable and movable within inclined tracks 57, and movable along track portions 53. On the rear edges of end members 11 and 12 are snap fasteners 59 adapted to engage spring tongs 59' situated near the rear edges of the transverse angles 62, these tongs 59' being below projections 76 of locking bars 74 as best shown in Figure 4, the said projections 76 being adapted to engage slots 60 on the inner walls of end members 11 and 12 for locking purposes.

In order to utilize the rear frame as a companion or twin bed with the main frame or to detach the same as an independent bed, very little effort is required so that the strength of the 75

housewife or operator is not taxed. The party who desires to make use of the sofa bed as a twin bed or two independent beds, stands behind the structure and applies outward pressure on operating member 69 thereby withdrawing legs 65 from collapsed position into rigid open position by the operation of rods 71. Links 73 cause the projections 76 of locking bars 74 to become disengaged from slots 60. At this stage of operation, while the legs are in maximum distended position, the rear frame 14 is held in place by the engagement of tongs 59' and snaps 59. However, by applying slight downward pressure on the rear frame 14, the tongs are disengaged and the frame falls outwardly and downwardly by the force of its weight about the trunnions 68 at the lower end of tracks 57, the operator controlling such movement. This rotation is mounted to continue downwardly until the casters 67, 67 mounted on the two front legs 65 touch the floor. In such position, the casters 67, 67 serve as fulcrums and the forward legs as lifting levers whereby upon application of slight downward pressure on the rear of frame 14, trunnions 68, 68 are forced upwardly along tracks 57. In the upward course of the trunnions, the lower end of the mattress or mattress cushions 18, normally resting on platform 42 is engaged by lifter projections 18', 18' situated near the ends of the lower or forward horizontal angle 61 whereby the mattress 18 is carried along with the displacement of frame 14 and properly spaced thereon.

When frame 14 has reached its first horizontal position and is resting on legs 65, trunnions 68 appear at the upper end of the outer wall 55 in track 57 and the frame 14 is spaced from the stationary frame 13. At this time frame 14 may be removed from frame 13 by a slight lift and rearward movement to clear the top of walls 55. Upon inward movement of the rear frame 14, trunnions 68 engage the horizontal track portions 53 until angle 61 abuts angle 25 thereby bringing about a twin bed arrangement.

In order to return the rear frame 14 to its upright position, it is pulled outwardly so that trunnions 68 are positioned against wall 55 at the top of tracks 57. Thereafter, the frame is slightly lifted from the rear utilizing the casters 67 as fulcrums whereupon the trunnions 68 descend down tracks 57 by the action of gravity thereby carrying frame 14 into an inclined upright position. The frame is engaged against the end members 11 and 12 by the engagement of tongs 59' in snaps 59. Thereafter, operating bar 69 is forced inwardly away from the operator to collapse legs 65 and in so doing projections 76 of locking bars 74 penetrate openings 77 in transverse angles 62 to engage slots 60 for locking the frame in end members 11 and 12.

The sofa bed above described has as one of its chief features the facility with which it is convertible either into a twin bed or an independent and detached single bed and vice versa. This feature is accomplished by the construction and position of the track members secured to the inner walls of end members 11 and 12. Moreover, the permanent locking means between the rear frame 14 and the end members 11 and 12 are controlled by the opening and closing of rear frame legs 65. Furthermore, the bedding compartment of the studio bed is accessible through front panel 34 which may be in the form of a drawer instead of in the form of a compartment closed by a panel 34. The lifters

18' are significant in that the mattress 18 is properly spaced on frame 14 when the latter is drawn to horizontal position. The mattress support 42 on the other hand is significant when frame 14 is brought from the horizontal to the upright position, for during this operation mattress 18 slides downwardly and comes to rest on platform 42.

In the opening of legs 65, although the drawings, especially Figure 5, show these legs when distended to be in vertical position, nevertheless the said legs may assume an outwardly inclined position to prevent buckling thereof. The outward inclined position of leg 65 may be brought about by exerting more outward pressure on operating bar 69 as shown in Figure 5, the outward position of legs 65 being limited by the engagement of the ends of locking bars 74 against transverse angles 62.

I wish it understood that minor changes and variations in the integration, location, material, combination and sub-combination of parts, may all be resorted to without departing from the spirit of the invention and the scope of the appended claims.

I claim:

1. In a sofa bed having end supporting members, a main stationary frame secured thereto, a rear upright frame swingably and slidably secured at one end to said end supporting members, collapsible legs having rollers for said rear frame, means to detachably secure the rear frame at the other end to said supporting members, the rear frame when released from said securing means being swingable outwardly to touch the floor on the rollers of the forward legs during distention thereof, the said rollers serving as fulcrums to slide the rear frame upwardly to horizontal position adjacent the main frame.

2. In a sofa bed having end supporting members, a main stationary frame secured thereto, a rear upright frame swingably and slidably secured at the lower end to said end supporting members, collapsible legs having rollers for said rear frame, means to detachably secure the upper end of the rear frame to said supporting members and being partly operable by the opening and closing of said collapsible legs, the rear frame, during the distention of the legs opening said securing means being swingable outwardly to touch the floor on the rollers of the forward legs, the said rollers serving as fulcrums to slide the rear frame upwardly to horizontal position adjacent the rear frame.

3. In a sofa bed having end supporting members, a main stationary frame secured thereto, a rear upright frame having collapsible legs with rollers on the ends thereof, guiding means on the end supporting members to swingably and slidably secure the lower end of said rear upright frame, means to detachably secure the rear upright frame at the upper end to said supporting members partly operable by the movement of the collapsible legs, the rear upright frame when released from said securing means during distention of the legs being swingable outwardly to bring the rollers of the forward legs into contact with the floor, the said rollers serving as fulcrums to slide the rear frame upwardly on the said guiding means to horizontal position adjacent the frame.

4. In a sofa bed having end supporting members, a main stationary frame secured thereto,

a rear upright frame at the lower end being swingably and slidably engageable with said supporting members, collapsible supporting means carried by said rear frame, locking means to detachably secure the upper portion of the rear upright frame to said supporting members and being operable by the opening and closing of said collapsible supporting means to permit the outward rotation of the rear frame to bring a portion of the supporting means into contact with the floor, the same serving as fulcrums to slide the rear frame upwardly to horizontal position adjacent the stationary frame, means to horizontally slide the rear frame to desired position adjacent the stationary frame.

5. In a sofa bed having end supporting members, a main stationary frame secured thereto, a detachable rear upright frame at the lower end being swingably and slidably engageable with said supporting members, collapsible supporting means carried by said rear frame, locking means to detachably secure the upper portion of the rear upright frame to said supporting members and being operable by the opening and closing of said collapsible supporting means to permit the outward rotation of the rear frame to bring a portion of the supporting means into contact with the floor, the same serving as fulcrums to slide the rear frame upwardly to horizontal position adjacent the stationary frame, means to horizontally slide the rear frame to desired position adjacent the stationary frame.

6. In a sofa bed having end supporting members, a main stationary frame secured thereto, a rear upright frame at the lower end being swingably and slidably engageable with said supporting members, collapsible supporting means carried by said rear frame, locking means to detachably secure the upper portion of the rear upright frame to said supporting members and being operable by the opening and closing of said collapsible supporting means to permit the outward rotation of the rear frame to bring a portion of the supporting means into contact with the floor, the same serving as fulcrums to slide the rear frame upwardly to horizontal position adjacent the stationary frame, a supporting platform carried by the stationary frame to support a mattress for the rear frame in upright position, lifting means carried by the rear frame adapted to centrally position the said mattress on the rear frame during the course thereof to horizontal position.

7. In a sofa bed having end supporting members, a main stationary frame secured thereto, a rear upright frame at the lower end being swingably and slidably engageable with said supporting members, collapsible supporting means carried by said rear frame, locking means to detachably secure the upper portion of the rear upright frame to said supporting members and being operable by the opening and closing of said collapsible supporting means to permit the outward rotation of the rear frame to bring a portion of the supporting means into contact with the floor, the same serving as fulcrums to slide the rear frame upwardly to horizontal position adjacent the stationary frame, a compartment within the stationary frame having an opening intermediate the front edges of the supporting members.

PHILIP CUTLER.
